UNITED STATES PATENT OFFICE.

EVERETT C. KLINE, OF CINCINNATI, OHIO, ASSIGNOR TO THE LAMINATED METAL PRODUCTS COMPANY, OF CINCINNATI, OHIO, A CORPORATION OF OHIO.

LOCK AND LOCK MOUNTING.

Application filed December 24, 1921. Serial No. 524,607.

To all whom it may concern:

Be it known that I, EVERETT C. KLINE, a citizen of the United States of America, and resident of Cincinnati, in the county of Hamilton and State of Ohio, have invented a new and useful Improvement in Locks and Lock Mountings, of which the following is a specification.

My invention relates to that type of lock generally employed on safety deposit boxes in safety deposit vaults as is also set forth in my co-pending application Serial No. 524,606, filed December 24th, 1921. In the ordinary deposit boxes referred to, and employing keys, it is possible by hammering upon the shank of the lock, to break the lock from the door of the deposit box. These boxes have also been broken into by having the hinges of the door broken, and the hinged end of the door being then withdrawn from the mouth of the box.

An object of my invention is to provide a lock and lock mounting, adapted to be used with safety deposit boxes, wherein it will be impossible from the outside of the box, to separate the lock from the door of the box without demolishing the entire door.

Another object of my invention is to combine a lock and mounting which will permit ready replacement or change of locks.

Another object is to provide a simple and efficient device to accomplish these purposes.

These and other objects are attained by the means described herein in which:

Fig. 1 is a front elevation of a deposit box of the type generally encountered in safety deposit vaults but to which a lock embodying my invention has been applied.

Fig. 2 is an enlarged sectional view on line 2—2 of Fig. 1.

Fig. 3 is a sectional view on line 3—3 of Fig. 2.

Fig. 4 is a perspective view from the rear of the door, showing the door partly open.

Safety deposit boxes are ordinarily built in tiers or rows and each box has a door 1 which may be opened, closed and locked. To lock and unlock these doors it is generally necessary to have two keys, one key generally being retained by the bank and the other by the renter of the safety deposit box. Although I have shown a lock embodying my invention as being a two key lock, same may be readily applied to other types of locks.

The door 1 has inwardly extending sides 2 and 3 which are disposed at the top and bottom respectively of the door and have formed between them a way or seat 4 within which may be disposed a lock 5 the shanks 6 of which extend through slots 7 in the front wall of the door. The keys wherewith the lock bolt 8 is actuated are inserted into the shanks 6. The sides 2 and 3 have U shaped slots 9 formed in their inner surfaces, said slots extending longitudinally of the door and extending in substantial parallelism with one another. A bar 39 comprising an intermediate portion 11 from the opposite sides and ends of which extend in substantial parallelism the body 10 and a flange 12, which body is adapted to have its opposite edges 13 and 14 seated in the grooves 9 in the door. The grooves are so positioned in the sides of the door that when the body 10 is seated upon the door, the body of the bar engages the rear wall of the lock 5. The intermediate portion 11 of the bar has a slot 15 through which the bolt 8 may be reciprocated. The flange 12 of the bar engages the rear wall 16 of the door. A block 17 is mounted on the inner surface of the wall 18 of the safety deposit chamber 19. The block 17 has a slot 20 in which the bolt 8 may lodge. The forward end of the block 17 is disposed at such a place that when the door is closed the inner surface of the flange 12 will engage the forward end of the block 17. The wall 18 is flared outwardly as shown at 21, and the edge of the door 22 is tapered so as to be complementary to the flared portion of the wall 18 whereby a snug closure is attained. The wall 23 of the box has mounted upon it a block 24 the forward end of which lies immediately adjacent the end 25 of the bar 39 when the door is closed. A plate 26 is mounted upon the interior surface of the wall 23 and has a shoulder 27 which engages the shoulder 28 formed on the wall 23. When the door is closed the end 25 of the plate 39 lies intermediate the plate 26 and the block 24. The plate 26 is secured in position by screws 29 the heads of which lie in slots 31 formed in the hinge plate 32 secured upon the door 1 by means of screws 33, the heads of which in turn may lodge in slots 34 formed in the plate 26, when the door is closed. The plate 26 and the hinge plate 32 carry lugs or hinge members 35 and 36 respectively which are piv-

totally secured upon one another by suitable pivots 37.

By referring to Fig. 2 it is apparent that any blows delivered on the door will be resisted by the blocks 17 and 24. In event the hinges are broken from the door, the end 25 of the bar 39, overlapping the plate 26 precludes that end of the door which carries the hinge plate 32 from being withdrawn from the mouth of the box. Any force directed upon the shank 6 of the lock is transmitted to the bar 39 and from the bar 39 to the blocks 17 and 24.

What I claim is:

15 A lock and mounting comprising a box having a mouth, a door having a substantially U shape, the sides or arms of which are grooved, said grooves opening upon one another, and the base or front of the door

having a slot, a bar slidably mounted in the 20 grooves in the sides of the door, whereby a chamber is formed within the door, a lock within the chamber to which access may be had thru the slot in the door, hinges mounting the door on the box, and means on the 25 sides of the box adapted to be engaged by the bar and the lock bolt when the door is closed, whereby the lock is precluded from separation from the door, and the bar precludes withdrawal of the hinged end of the 30 door from the mouth in event the hinged connection of the door upon the box is severed.

In testimony whereof, I have hereunto subscribed my name this 19th day of December, 1921.

EVERETT C. KLINE.
